AGITATOR

Alexander J. Roubal, Milwaukee, Wis., assignor to Allis-Chalmers Manufacturing Company, Milwaukee, Wis., a corporation of Delaware

Application December 14, 1945, Serial No. 634,931

1 Claim. (Cl. 259—108)

1

This invention relates to improvements in agitators for fluid mixtures of the type in which a substantially vertical agitator shaft carrying fluid impellers is rotated in a tank to mix or agitate the contents of the tank for the purpose of creating or maintaining a homogeneous mixture of fluids or fluids and solids.

More particularly the invention relates to an improved impeller for agitating a fluid mixture in a tank such impeller being readily adaptable to various consistencies of fluid mixtures to be treated, and improved means for mounting the impeller in the tank.

An object of the invention is to provide an impeller in which a fluid propeller or agitating means is attached to a rotating shaft by means providing for readily securing the propeller in any one of a plurality of positions of adjustment axially of the shaft.

A further object of the invention is to provide cooperating axial and radial impellers for causing fluid to be efficiently propelled downwardly along the shaft and outwardly across the tank bottom.

A still further object is to provide an impeller with an improved submerged bearing for location of the lower end of the shaft in the tank, in which the bearing is properly protected from entrance of liquids by the diving bell principle, and provision is made for lifting and lowering of the bearing structure through a body of liquid in the tank without admission of liquid to the operative bearing surfaces.

A still further object is the combination of the impeller and bearing structure mentioned above with a device for maintaining a gaseous atmosphere in the bell and also blowing settled solid material free of the bell and agitator blades extending from the bell.

The above mentioned and still further objects and advantages may be secured and carried into practical effect as described below with reference to the accompanying drawing in which:

Fig. 1 is a vertical sectional view of an agitator according to the present invention;

Fig. 2 is an enlarged vertical sectional view of the submerged shaft end and bearing structure shown in Fig. 1;

Fig. 3 is a cross sectional view taken on the line III—III of Fig. 2;

Fig. 4 is a top elevation of the bearing receiving base shown in Fig. 2 with bearing structure removed.

In a preferred embodiment of the invention illustrated in the drawing, a tank 1 for contain-

ing a body of fluid mixture to be agitated, has a frame 2 extending across the top, on which is mounted an agitator drive mechanism 3 for supporting and rotating an impeller shaft 4 extending vertically downward into and substantially to the bottom of tank 1. The shaft supporting assembly 2—3 and shaft 4 is arranged so as to be removable upwardly from and replaceable downwardly to the operative position illustrated.

Secured to shaft 4 intermediate its length, and within the tank when the shaft 4 is in operative position, is a fluid impeller, which in the present embodiment is a propeller 6. Propeller 6 is arranged to propel fluid mixture generally downwardly in the vicinity thereof, along shaft 4, when the shaft is rotated in operating direction on its axis.

As shown, and according to the present invention, the propeller 6 is keyed in axially slideable driven relation to shaft 4. A conventional keyway is shown at 7 for reception of a conventional key (not shown) suitably engaging the hub 8 of propeller 6 in known, suitable, manner to prevent relative rotation of the propeller and shaft in operation. Propeller locating spacer sleeves 9 are provided to fit slidably on the propeller mounting portion of the shaft 4. A shoulder 11 forms an abutment limiting the axial movement in one direction of the sleeves 9, and hub 8, which are arranged in selected order on the shaft 5 in series abutting relation to shoulder 11. It will be clear that if the hub 8 abuts 11 with all sleeves 9 between it and the lower shaft end, the propeller 6 will occupy an uppermost position shown by broken lines in Fig. 1; and if all spacer sleeves 9 are placed above the hub 8 the propeller 6 will occupy a lowermost position shown by broken lines in Fig. 1, as compared with the position of the propeller 6 as indicated in full lines in Fig. 1. The sleeves 9 and hub 8, assembled in selected order on the shaft 4, are clamped in position between shoulder 11 and clamp plate 12 as shown in Fig. 1. Plate 12 is secured, as by cap screws 13, to the lowermost end of shaft 4, and projects beyond the shaft periphery sufficiently to engage the sleeves 9 or hub 8 in clamping relation, either directly (not shown), or indirectly through an additional end spacer, which, in the drawing, is shown as a flanged coupling member 14 adapted for attachment of a bearing housing member 16, described hereinbelow.

Bearing housing 16 is externally provided with generally radially extending blades 17 forming an auxiliary impeller for centrifugally impelling

fluid radially outwardly near the bottom of tank 1, thus cooperating with axial propeller 6 to cause a flow of fluid down along the shaft and outwardly over the tank bottom. Adjustment of the propeller 6 axially relative to the auxiliary impeller 17 will provide for optimum effectiveness on various fluid mixtures according to their flow characteristics.

In order to provide a steady bearing for positively locating the submerged end of shaft 4 in operative position against displacement by laterally acting forces, a bearing surface, such as cylindrical stub shaft 18, is provided within the housing 16. Housing 16 is arranged to form a fluid tight bell housing adapted to retain a gaseous fluid atmosphere under pressure, which will prevent access of a liquid mixture in tank 1 to the bearing surface of 18 so long as the housing 16 is fluid tight down to a level substantially below any part of the bearing surface of 18.

In radial bearing engagement with the bearing surface of 18 is a relatively rotatable bearing member or bushing 19 which may be provided, as shown, with a self lubricating liner 21 forming an actual bearing surface. Bearing member 19 is preferably closed at the bottom to make it cup shaped, but need not be so closed provided it has no opening extending below the fluid tight portion of the bell housing 16. As shown, bushing 19 is formed with a frusto-conical external surface 22 which forms a pilot bearing, or lateral thrust transmitting and centering surface adapted to engage a complementary surface 23 on a pilot bearing base 24, in the tank bottom. Further, the bushing 19 may have a lateral extension or extensions 26 cooperating with a retaining ring or lifter plate 27, which is secured to the housing 16 after assembly of bushing 19 on stub shaft 18, to limit axially outward motion of bushing 19 relative to housing 16.

Pilot bearing base 24 may be formed as shown, as an annulus 28 supported by an open cage 29 secured to the tank bottom in any suitable manner. However, any suitable device for freely receiving bushing 19 in lateral thrust transmitting relation may be substituted for base 24.

In order to provide for establishing, maintaining or renewing a gaseous atmosphere under pressure within the bell housing 16, and for admission of excess air, a pipe 31 is provided with nozzle tip outlet 32 vertically below the opening of bell housing 16 when in operative position. Pipe 31 is connected with a suitable source of gaseous fluid under pressure (not shown).

In operation of the agitator described above, a fluid mixture, such as a liquid with fine solids suspended therein, is placed in the tank 1. Rotation of shaft 4 causes propeller 6, properly set to best level for the particular material being treated, to propel liquids or liquid suspensions downward along shaft 4. Impeller blades 17 cause liquid surrounding housing 16 to be impelled radially outward over the bottom of tank 1. These actions cooperate to create an optimum agitation of fluids in the tank. Supply of air through pipe 31 and nozzle 32 maintains a gaseous atmosphere under pressure in housing 16 which, by the diving bell principle, prevents the entrance of any liquid into bell 16 above a level determined by the fluid pressure within bell 16. The liquid level in bell housing 16 is maintained sufficiently low to prevent intrusion of liquid into

the relatively rotating interengaging bearing surfaces of elements 18 and 21.

Occasionally, for example as a result of stoppage of the impeller, solids may collect in the vicinity of the opening of bell 16 and around the blades 17 which would, if not removed, tend to impede rotation of the impeller and tend to intrude into the housing 16. To prevent this, and to effectively maintain the atmosphere in bell 16, excess air may be intermittently or continuously forced through pipe 31 and nozzle 32. Excess air so supplied will escape around the mouth of the bell 16 and force any settling solids away from the vicinity of the housing, bearing and impeller structure, thus increasing the effectiveness of the device in maintaining or obtaining a homogeneous mixture in the tank.

When it is necessary to lift shaft 4 with its impellers, for any reason such as repairs, it will be seen that lifter plate 27 will engage projections 25 and lift bushing 19 with the housing 16. This provides for lifting of the whole operative bearing structure with the shaft. Reinsertion of the agitating mechanism in a full tank will be facilitated by provision of the self-centering pilot surfaces 22 and 23. Since surface 23 is supported by a cage, no fluid can be trapped when surface 22 is engaging surface 23. Accordingly, the shaft 4 may be freely lifted and lowered from and to operative position without danger of fouling of the bearing by the liquid mixture in the tank.

While a specific embodiment of the invention has been illustrated and described, it will be understood that the invention is intended to include such modifications and equivalents as may be within the scope of the appended claim.

It is claimed and desired to secure by Letters Patent:

In an agitator having a substantially vertical rotating shaft, a bearing member engaging said shaft in relatively rotatable relation, said shaft being located at its foot by engagement of said bearing member with a surface below the level of a body of liquid, a downwardly open bell housing carried at the foot of said shaft and surrounding said relatively rotatable member, in upwardly fluid tight relation, agitator blades extending radially from the external surface of said bell housing for operative rotation with said shaft, and means for supplying a gaseous fluid under pressure to said bell housing for maintaining a gaseous atmosphere within said bell and blowing particles of settled solid matter away from the vicinity of said bell housing and blades.
